CLAIM

The ornamental design for a pool access apparatus for the disabled, as shown and described.

DESCRIPTION

FIG. 1 is a perspective view of a pool access apparatus for swimming pools embodying my new design; FIG. 2 is a left side elevation thereof, the right side being a mirror image;

FIG. 3 is a perspective view corresponding to FIG. 1 but showing the two main parts of the access apparatus separated from one another;

FIG. 4 is a side elevation corresponding to FIG. 2 but showing the two main parts of the access apparatus separated from one another;

FIG. 5 is a front elevation thereof;

FIG. 6 is a rear elevation thereof;

FIG. 7 is a top plan view thereof;

FIG. 8 is a bottom plan view thereof;

FIG. 9 is a perspective view thereof with the upper step portion omitted; and

FIG. 10 is a side elevational view thereof with the upper step portion omitted.

FIG. 1

FIG. 2

FIG. 5FIG. 6FIG. 7FIG. 8
